UNITED STATES PATENT OFFICE

LESLIE S. HACKNEY, OF ST. PAUL, MINNESOTA.

VENTILATING DEVICE.

988,463.

Specification of Letters Patent.

Patented Apr. 4, 1911.

Application filed February 13, 1908. Serial No. 415,645

To all whom it may concern:

Be it known that I, LESLIE S. HACKNEY, of St. Paul, Ramsey county, Minnesota, have invented certain new and useful Improvements in Ventilating Devices, of which the following is a specification.

In railway coaches, particularly those of the parlor sleeping car type where double, tight-fitting windows are employed, the need 10 of some ventilating apparatus other than those provided in the roof of the car, has been generally recognized. The windows are usually closed to prevent the entrance of cinders, smoke and dust, and the interior of the 15 car, particularly at night, becomes very close and stifling. Many passengers who would prefer to admit fresh air through the windows cannot do so on account of the draft and the danger of taking cold. This is particularly true as regards the upper berths 20 where the position of the ventilators when open tends to admit drafts of air directly upon the person in the berth.

To overcome these objections to railway 25 coaches generally and particularly to parlor and sleeping cars, and to remove one of the discomforts and annoyances of traveling, is the object of my present invention.

A further object is to provide a ventilating apparatus of simple, compact construction, capable of application to any type or 30 make of railway coach.

The invention consists generally in various 35 constructions and combinations, all as hereinafter described and particularly pointed out in the claims.

In the accompanying drawings forming 40 part of this specification, the figure represents a longitudinal vertical sectional view of one end of a railway coach with my invention applied thereto.

In the drawing, 2 represents the floor of a sleeping car and 3 the side walls of the car. Under the seats 4 I provide a series of registers 45 5 leading to a pipe 6 arranged within the wall near the floor line and extending from end to end of the car. This pipe enters the lower end of a pump cylinder 7, and a pipe 8 leads from the pump cylinder down 50 through the floor of the car to a point where the foul air collected in the pipe 6 through the registers 5 may be discharged. Check valves 9 and 10 are provided in these pipes by means of which the flow of air there-through is controlled, one valve being 55 opened as the other closes. In the upper

walls of the car is a pipe 11 extending lengthwise thereof, having depending branches 12 at intervals extending downwardly between the windows 13 and provided with registers 14 through which fresh air may be discharged into the car and into the upper and lower berths when made up. These registers may be adjusted to regulate the admission of the air. The pipe 11 extends to a chamber 15 inclosing an ice-box 16, and a pipe 17 leads from the ice-box to the upper end of the cylinder 7 and communicates with the open air through a pipe 18 provided with a check valve 19 which opens when the 70 plunger descends and closes when it ascends. Through the pipe 18 the pure fresh air is taken into the car. A plunger 20 is provided within the pump cylinder and a driving mechanism 21 is connected to the pump 75 plunger and is operated from an electric motor 22 or other suitable power. A valve 23 is provided in the pipe 17 and a spout 24 extends from the ice-box 16 through the chamber 15 to a water tank 25. The pipe 17 80 communicates also with a box 26 wherein a radiator 27 is arranged, and pipes 28 and 29 connect the pipe 17 and the box 26 with the pipe 11. A valve 30 is provided at the junction of the pipes 28 and 17. I am thus 85 able to direct the fresh pure air through the chamber around the ice-box 16 and through the box 26 at will and cool the air or heat it before discharging it into the car. By closing the valves 23 and 30 leading to the 90 ice-box or radiator, I can deliver fresh air to the pipe 11 through pipes 17 and 28 without cooling or heating it.

This apparatus may be arranged within a small compartment adjoining the wash room 95 of the car where it is easily accessible for the purpose of operation and control.

I prefer to provide a thermostat for controlling the valves of the heating and ventilating apparatus, the thermostat proper 100 being indicated by reference numeral 23' and arranged on the wall of the car at a suitable distance from the floor. This thermostat is connected by the usual wires (not shown), with motors M and M' arranged 105 near the pipes of the heating ventilating apparatus and connected by a suitable crank mechanism with the valves 30 and 23. These connections are so adjusted that the operation of one motor will direct the supply of 110 air through the cooling tank, and the operation of the other motor will direct the air

through the heating radiator. I am thus able to control the supply of the cool and warm air to the car according to the temperature of the car.

5 I have shown this device in connection with a sleeping car but do not wish to be confined to such use as the invention is capable of application on tram or traction cars of all kinds and in the staterooms of steam 10 ships and in buildings of various descriptions.

I claim as my invention:

1. The combination, with a car having a series of exit openings in its lower walls, a 15 pipe communicating with said openings, a pump connected to said pipe, the upper walls of said car having a series of air inlet openings, a pipe communicating with said openings and with said pump, said pump 20 having pipes leading to the open air and operating to withdraw foul air from the bottom of the car and force fresh air through said inlet openings into the car, and cooling and heating chambers through which the 25 fresh air may be directed before entering the car, said cooling and heating chambers being interposed in the line of piping which communicates with the end of the pump opposite to the end into which the foul air is 30 drawn from the bottom of the car.

2. The combination with a chamber to be ventilated, heated, or cooled, of a pump, a

foul air eduction pipe having inlet openings along the lower portion of said chamber and opening into the pump on one side thereof, 35 a foul air discharge pipe leading out from the same end of the cylinder, a fresh air inlet pipe opening into the opposite side of the pump, a fresh air supply pipe leading from the fresh air inlet side of the pump and 40 extending through said chamber along the upper portion thereof and provided with downwardly extending branches opening into the upper and middle portions of the chamber, an air cooling chamber in communication with said fresh air-supply pipe, a heating chamber in communication with the fresh air-supply pipe, and valves located in the fresh air-supply pipe for cutting off the air from either the cooling 45 chamber or heating chamber, to supply either cooled or heated air to the chamber, or from both so as to supply air at the temperature of the outside atmosphere, said 50 pump, cooling and heating chambers being 55 located at the end of the chamber whence the fresh air is introduced and the foul air is discharged, substantially as described.

In witness whereof, I have hereunto set my hand this 27th day of January 1908.

LESLIE S. HACKNEY.
